UNITED STATES PATENT OFFICE.

AMANDA BEUTNER, OF NEW YORK, N. Y.

HAT OR BONNET PIN PROTECTOR.

1,166,172.

Specification of Letters Patent. Patented Dec. 28, 1915.

Application filed May 12, 1914, Serial No. 838,086. Renewed August 27, 1915. Serial No. 47,676.

To all whom it may concern:

Be it known that I, AMANDA BEUTNER, a citizen of the United States, residing at New York, in the county of New York and State 5 of New York, have invented certain new and useful Improvements in Hat or Bonnet Pin Protectors, of which the following is a specification.

This invention relates to improvements in 10 hat pin protectors, and more especially to an improvement over my former Patent No. 1,026,942.

The object of this invention is the provision of a hat pin protector which is permanently secured to the brim of a hat, thereby preventing its becoming lost, and which is 15 adjustable thereon, for the purpose of positioning the same in alinement with the hat pin after the latter has been inserted 20 through the crown of the hat.

A further object of this invention is the provision of a hat pin protector which is 25 slidably located and rotatable in its supporting member, the latter being of telescopic formation and hingedly attached to the brim of a hat.

A further object of this invention is the provision of a hat pin protector which will 30 be comparatively simple and inexpensive to manufacture, reliable and efficient in use and readily operated.

With the above and other objects in view, the present invention consists in the combination and arrangement of parts herein- 35 after more fully described, illustrated in the accompanying drawings, and particularly pointed out in the appended claims, it being understood that changes may be made in the form, proportion, size and minor details 40 without departing from the spirit or sacrificing any of the advantages of the invention.

In the drawings:—Figure 1 is a side elevation of a hat showing my improved pro- 45 tector applied thereto. Fig. 2 is a detail view of a fragment of the brim of a hat showing my protector applied thereto in full lines, and illustrating its manner of adjustment thereon in dotted lines. Fig. 3 is 50 a vertical sectional view taken through the hat pin protector.

Referring to the accompanying drawings by similar characters of reference throughout the several views, the numeral 4 designates in general a lady's hat which consists 55 of the usual crown 5 and brim 6, to the lat-

ter of which my improved protector 7 is attached. This protector 7 consists of a supporting bearing 8 formed upon the upper end of a tubular casing 9 restricted at its 60 lower end to produce a stop shoulder 10.

A supporting rod 11 is slidably located in the tubular casing 9 and is provided at its upper end with a circular head which is 65 slidably located and rotatable in the said tubular member 9, being of a size equal to the diameter of said tubular member but greater in size than the opening in the shoulder 10, which prevents the displacement of the said supporting bearing 8 from the supporting 70 rod 11, yet permits of the desired adjustment thereof.

The lower end of the rod 11 is bifurcated as at 12 terminating in oppositely extending lateral alining fingers 13 which are hingedly 75 attached to the brim 6 of the hat 4 by the bearing clips 14. A pin point engaging element 15 is slidably located in the supporting bearing 8 and is provided at its opposite ends with a shoulder 16 and head 17, respectively, of any suitable ornamentation, the said head and shoulder being designed to contact with the opposite sides of the bearing 8 which permits of the longitudinal ad- 80 justment of the element 15 therein yet pre- vents any undesired displacement from the said bearing 8 and limits the movement of the pin engaging element in its opposite di- 85 rections.

The point engaging element 15 is formed 90 with a longitudinal socket 18 of a size and shape adapted to engage the point of the pin 19, as clearly shown in Fig. 1 of the drawing.

The device is used as follows:—The pin 95 19 is first inserted through the crown 5 of the hat 4 and the point engaging element 15 moved into alinement therewith. The element 15 is then moved in the bearing in- 100 wardly toward the crown of the hat and into engagement with the point of said pin 19, in which position it is held by frictional en- gagement, caused by the rotation of the head of the pin engaging element upon the point of the pin, by holding the pin stationary 105 and at the same time exerting pressure in- wardly upon said head of the pin engaging element. It will be noted in this connection that the hat pin may be inserted in any de- 110 sired position into the hat, as long as the point thereof projects through the end of the hat adjacent the protector 7 which latter

can be swung upon its pivotal point and extended to engage the point of the pin in any desired position. When the head 17 is moved into engagement with the point of the pin, 5 after the latter is inserted through the hat, the said head can be rotated which causes the pin to bind in the socket 18 thereby holding said pin against displacement. When it is desired to remove the pin a slight rotation 10 and outward movement of the head readily disengages said point of the pin from the socket 18.

From the foregoing disclosures taken in connection with the accompanying drawings, 15 it will be manifest that a hat pin protector is provided for, which will fulfil all the necessary requirements of such a device.

What I claim is:

1. In a hat pin protector such as described, a supporting bearing, a point engaging element rotatable and slidable in said bearing, means for preventing the displacement of the pin engaging element from said bearing, a tubular extension projecting 25 from said bearing, said tubular extension being restricted at one end thereof, a rod slidable and rotatable in said tubular extension, a head formed upon said rod and disposed within said tubular extension whereby 30 said point engaging element can be moved to and from the brim of a hat while positioned at any angle relative to said hat, one end of said rod being bifurcated, and bearing clips engaging the bifurcated ends of said rod whereby said rod can be hingedly secured to the brim of a hat.
2. In a hat pin protector, a supporting bearing having an opening provided therein, an elongated pin engaging element slidably 40 mounted within said opening in the bearing, a head formed upon one end of the pin engaging element and arranged to contact with the bearing for limiting the inward movement

of the pin engaging element, a tubular extension formed upon the bearing, a rod 45 adapted to be pivotally connected to the brim of a hat and slidably mounted within said tubular extension, whereby the pin engaging element may be moved laterally of the hat, and adjusted to and from the pivotal point of said rod, a head formed upon said rod within the tubular extension, and the end of the tubular extension being crimped inwardly to engage the rod and prevent displacement of the rod from within 50 the tubular extension.

3. In a hat pin protector, a supporting rod, means for pivotally attaching the supporting rod to the brim of a hat, a tubular rod slidable and rotatable upon said supporting rod, a bearing formed upon said tubular rod, a pin engaging element slidable and rotatable in said bearing, a shoulder formed upon the pin engaging element for limiting the movement of the same in one 60 direction within the bearing, and a head formed upon the opposite end of the pin engaging element for limiting the movement of the same in the opposite direction.

4. In a hat pin protector, a supporting 70 rod, a tubular rod slidable and rotatable upon said supporting rod, a pin engaging element slidable and rotatably supported in said supporting rod, a shoulder formed upon the pin engaging element for limiting the 75 movement in one direction relative to the supporting rod, and a head formed upon the opposite end of the pin engaging element for limiting the movement of the latter in the opposite direction.

In testimony whereof I affix my signature in presence of two witnesses.

MRS. AMANDA BEUTNER.
